DIFFERENTIAL PUMP

James K. Douglas, Shorewood, Wis., assignor to
The Oilgear Company, Milwaukee, Wis., a corporation of Wisconsin

Application April 16, 1936, Serial No. 74,740

11 Claims. (Cl. 103—161)

This invention relates to pumps of the type ordinarily employed for supplying liquid to hydraulic motors to drive the same. A pump of this type has heretofore been so constructed that, when connected in circuit with a non-differential motor, the volume of liquid returned to the pump cylinder from the circuit is the same as the volume supplied by the pump to the circuit except for the volume lost due to leakage or slip.

The present invention has as an object to provide a pump which under all conditions of operation will discharge into a hydraulic circuit a greater volume of liquid than its cylinders receive therefrom.

A non-differential motor driven by liquid supplied thereto from a pump embodying the present invention may have a back pressure maintained thereon without passing the entire motor discharge through a resistance.

Other objects and advantages will appear from the description hereinafter given of a pump in which the invention is embodied.

According to the invention in general aspects, the pump is so constructed that the number of its cylinders discharging into a hydraulic circuit is greater than the number of its cylinders receiving liquid therefrom.

The invention is exemplified by the pumps illustrated somewhat schematically in the accompanying drawings in which the views are as follows:

Fig. 1 is a view taken on the line 1—1 of Fig. 2 and illustrating in central longitudinal section a reversible differential pump in which the invention is embodied.

Fig. 2 is a transverse section taken on the line 2—2 of Fig. 1.

Fig. 3 is a transverse section taken on line 3—3 of Fig. 1.

Fig. 4 is a sectional plan view taken on the line 4—4 of Figs. 1 and 3 and showing the channels through which liquid may flow to and from an external circuit.

Fig. 5 is a diagram showing the pump connected in circuit with a non-differential motor.

Fig. 6 is a view taken on the line 6—6 of Fig. 7 and illustrating in central longitudinal section a non-reversible differential pump in which the invention is embodied.

Fig. 7 is a transverse section taken on the line 7—7 of Fig. 6.

Fig. 8 is a transverse section taken on the line 8—8 of Fig. 6.

Fig. 9 is a sectional plan view taken on the line 9—9 of Figs. 6 and 8 and showing the chan-

nels through which liquid may flow to and from an external circuit.

Fig. 10 is a diagram showing the non-reversible pump connected in circuit with a differential motor, the reversing valve and the by-pass valve being shown in position to cause the motor to execute a working stroke.

Fig. 11 is a sectional view showing the reversing valve in position to cause the motor to execute a return stroke.

Fig. 12 is a sectional view showing the by-pass valve in position to by-pass the pump and thereby stop the motor.

For the purpose of illustration, the invention is shown embodied in pumps of the rolling piston type described and claimed in Ferris Patent No. 2,074,068 to which attention is directed for an explanation of the characteristics of rolling piston pumps.

Figs. 1 to 5

As shown in these figures, the pump has its mechanism arranged within and carried by a casing 1 which may be arranged upon and supported by a reservoir 2 containing the supply of liquid such as oil. Casing 1 is closed at its rear end by an end wall 3 of substantial thickness and at its front end by a removable front head 4 which is fastened to the end of casing 1 as by means of bolts 5.

Rear wall 3 has rigidly secured therein the rear part of a valve shaft or pintle 6 the front part of which extends into casing 1 and has formed therein two diametrically opposed main ports 7 and 8 and two diametrically opposed auxiliary ports 9 and 10.

The front part of pintle 6 has closely fitted thereon a rotatable cylinder barrel 11 which is ordinarily composed of a plurality of rigidly connected concentric sections and provided with a plurality of main cylinder ports 12 and a plurality of auxiliary cylinder ports 13.

Ports 12 are arranged in a circular row so that each port 12 may register with pintle ports 7 and 8 alternately as cylinder barrel 11 rotates. Likewise, cylinder ports 13 are arranged in a circular row so that each port 13 may register with pintle ports 9 and 10 alternately as cylinder barrel 11 rotates. In order that no two cylinder ports may open to a pintle intake port and to a pintle discharge port simultaneously, each row contains an odd number of ports, nine being shown.

Cylinder barrel 11 is adapted to be rotated by a drive shaft 14 which extends through front

head 4 and is journaled near its outer end in a bearing 15 carried by front head 4 and at its inner end by a bearing 16 arranged in the end of pintle 6. Shaft 14 drives cylinder barrel 11 through a driver 17 which is splined on shaft 14 and connected to cylinder barrel 11 by a universal driving connection 18.

Cylinder barrel 11 is provided with a plurality of radial cylinders 19 which are shown arranged in four circular rows with eighteen cylinders in each row. The cylinders in the three rear rows communicate with ports 12 and the cylinders in the front row communicate with ports 13, as shown in Fig. 1, and each two adjacent cylinders in each row communicate with each other, as shown in Fig. 2, so that each port 12 serves six cylinders and each port 13 serves two cylinders.

Each cylinder 19 has fitted therein a piston 20 having an arcuate contact face upon its outer end to engage a thrust ring 21 fixed upon the inside of an annular thrust member 22 which substantially encloses cylinder barrel 11.

Thrust member 22 is supported at its front and rear ends, respectively, in two anti-friction bearings 23 and 24 carried by a slide block 25 which is supported in casing 1 as by means of four slide plates 26 fastened to slide block 25 and four slide plates 27 fastened to the upper and lower walls of casing 1. The arrangement is such that slide block 25 may be shifted transverse to the axis of pintle 6 but is restrained from any vertical movement.

Slide block 25 is adapted to be shifted in one direction or the other by two servo-motors one of which has its piston 28 fastened to one side thereof and the other of which has its piston 29 fastened to the other side thereof. Piston 28 is fitted in a cylinder 30 which is formed in one side wall of casing 1 and closed at its outer end by a head 31 having an adjusting screw 32 threaded therethrough for limiting the movement of slide block 25 in one direction. Piston 29 is fitted in a cylinder 33 which is formed in the other side wall of casing 1 and closed at its outer end by a head 34 having an adjusting screw 35 threaded therethrough for limiting the movement of slide block 25 in the opposite direction.

Slide block 25 may be shifted in one direction by liquid supplied to cylinder 30 through a pipe 36 which is connected to head 31, and it may be shifted in the opposite direction by liquid supplied to cylinder 33 through a pipe 37 which is connected to head 34.

Liquid for operating servo-motors 28-30 and 29-33 may be supplied by an auxiliary pump such as an ordinary gear pump having its driving gear 40 fastened upon drive shaft 14 and its driven gear 41 fastened upon a stub shaft 42 which is fixed in front head 4. Gears 40 and 41 are arranged in a pump chamber 43 which is formed in front head 4 and closed at its rear by a plate 44 bolted or otherwise secured to front head 4.

Gear pump 40-41 has not been illustrated nor described in detail as it is of ordinary construction and as it is common practice to arrange such pumps in the manner shown. It is deemed sufficient to state that it draws liquid from reservoir 2 through a suction channel 45 and discharges it into a low pressure supply channel 46 as shown schematically in Fig. 5.

If pressure liquid is supplied through pipe 36 to cylinder 30, piston 28 will shift slide block 25 toward the right until piston 29 engages adjust-

ing screw 35 and, if pressure liquid is supplied through pipe 37 to cylinder 33, piston 29 will shift slide block 25 toward the left until piston 28 engages adjusting screw 32.

When cylinder barrel 11 is rotated and slide block 25 is shifted so that the axis of thrust member 22 is offset from the cylinder barrel axis, each piston 20 will move progressively outward during one half-revolution of cylinder barrel 11 and inward during the other half-revolution thereof, the frictional contact between pistons 20 and thrust rings 21 causing thrust member 22 to rotate substantially in synchronism with cylinder barrel 11. Liquid will fill the cylinders as the pistons move outward and be expelled from the cylinders as the pistons move inward, and the pump will deliver liquid in a direction and at a rate determined by the direction and the distance the axis of thrust member 22 is offset from the cylinder barrel axis.

If slide block 25 is shifted toward the right and cylinder barrel 11 is rotated in a counter-clockwise direction as viewed in Fig. 2, the pistons in the upper half of cylinder barrel 11 will move progressively inward and expel liquid from their cylinders into pintle ports 7 and 9 at a rate determined by the adjustment of screw 35, and liquid will flow through pintle ports 8 and 10 and fill the cylinders in the lower half of cylinder barrel 11. If slide block 25 is shifted toward the left, liquid will flow to the cylinders in the upper half of cylinder barrel 11 through pintle ports 7 and 9 and be expelled into pintle ports 8 and 10 from the cylinders in the lower half of cylinder barrel 11.

The cylinders in the three rear rows in cylinder barrel 11 are adapted to deliver liquid directly to and receive liquid directly from an external circuit, two pipes 50 and 51 of which may be connected to casing 1 in communication, respectively, with two passages 52 and 53 formed in the rear wall 3 thereof.

Passage 52 (Figs. 3 and 4) extends forward into communication with a passage 54 which extends upward and then laterally in rear wall 3 into communication with a passage 55 (Figs. 2 and 3) which extends radially into pintle 6 and then longitudinally thereof into communication with pintle port 7. Passage 53 extends forward into communication with a passage 56 which extends downward and then laterally in rear wall 3 into communication with a passage 57 which extends radially into pintle 6 and then longitudinally thereof into communication with pintle port 8.

The arrangement is such that the cylinders in the three rear rows of cylinder barrel 11 discharge either through port 7 into pipe 50 or through port 8 into pipe 51 and are supplied with liquid either through pipe 51 and port 8 or through pipe 50 and port 7 depending upon the direction in which the axis of thrust member 22 is offset from the cylinder barrel axis.

The cylinders in the front row of cylinder barrel 11 are adapted to deliver liquid to the external circuit and to be supplied with liquid from reservoir 2. In order that the pump may be reversed, that is, in order that the front row of cylinders may deliver liquid into either pipe 50 or pipe 51 and be supplied with liquid from reservoir 2 regardless of which pipe they deliver liquid into, the pump is provided with an automatic switch valve 60 which has a central head or piston 61 and two end heads or pistons 62 and 63

formed thereon and closely fitted in a bore 64 formed in rear wall 3 transversely thereof.

Valve pistons 62 and 63 control communication between bore 64 and the two ends of a passage 65 which is formed in rear wall 3 below bore 64 and parallel thereto. Passage 65 communicates through a check valve 66 with a suction pipe 67 which extends downward into the liquid in reservoir 2.

Valve piston 61 controls communication between a passage 68 and a passage 69, between passage 68 and a passage 70 and between passage 69 and a passage 71, all four of which are formed in rear wall 3.

Passages 68 and 69 connect bore 64 to passages 52 and 56 respectively. Passage 70 extends forward to a point beyond passage 68 and then it extends upward into communication with a passage 72 which is formed in pintle 6 and communicates with port 9. Passage 71 extends forward to a point beyond passage 56 and then extends upward into communication with a passage 73 which is formed in pintle 6 and communicates with port 10.

In order that valve 60 may be shifted automatically when the direction of liquid flow is reversed, passage 70 is connected to the left end of bore 64 by a passage 74 formed in rear wall 3, and passage 71 is connected to the right end of bore 64 by a passage 75 formed in rear wall 3.

When the axis of thrust member 22 is offset toward the right from the cylinder barrel axis and cylinder barrel 11 is rotated in a counter-clockwise direction as viewed in Fig. 2, the cylinders will discharge into pintle ports 7 and 9 and be supplied with liquid through pintle ports 8 and 10 as previously explained. The liquid discharged into port 7 will flow through passages 55, 54 and 52 into pipe 50 and the liquid discharged into port 9 will flow through passages 72, 70 and 74 to the left end of bore 64 and move valve 60 toward the right to the position shown in full lines in Fig. 3 and then it will flow from passage 70 through bore 64 and passages 68 and 52 into pipe 50 so that the output of all of the cylinders is combined into a single stream.

At the same time, the cylinders in the three rear rows will be supplied with liquid from the external circuit through passages 53, 58 and 57 and ports 8 and 12, and the pistons in the front row will draw liquid into their cylinders from reservoir 2 through suction pipe 67, check valve 66, passage 65, bore 64, passages 71 and 73 and ports 10 and 13.

When slide block 25 is shifted so that the axis of thrust member 22 is offset toward the left from the axis of cylinder barrel 11, the cylinders will discharge into pintle ports 8 and 10 and be supplied with liquid through pintle ports 7 and 9. The liquid discharged into port 8 will flow through passages 51, 56 and 53 into pipe 51 and the liquid discharged into port 10 will flow through passages 73, 71 and 75 to the right end of bore 64 and move valve 60 toward the left to the position shown in dotted lines in Fig. 3 and then it will flow from passage 71 through bore 64 and passages 69, 56 and 53 into pipe 51 so that the output of all of the cylinders is combined into a single stream.

At the same time, the cylinders in the three rear rows will be supplied with liquid from the external circuit through passages 52, 54 and 55 and ports 7 and 12, and the pistons in the front row will draw liquid into their cylinders from reservoir 2 through suction pipe 67, check valve 75

66, passage 65, bore 64, passages 70 and 72, and ports 9 and 13.

The pump thus delivers its entire output in a single stream and has a part of its cylinders supplied with liquid from one source and the remainder of the cylinders supplied with liquid from a different source in either direction of pump delivery.

For the purpose of illustration, the pump is shown in Fig. 5 as being connected by pipes 50 and 51 to opposite ends of the cylinder 80 of a non-differential motor and as having its servomotor pistons 28 and 29 operated by liquid supplied to cylinders 30 and 33 from gear pump 40-41 under the control of a reversing valve 81 to the casing of which pipes 36, 37 and 46 are connected.

Cylinder 80 has a piston 82 fitted therein and connected to two piston rods 83 and 84 which extend through opposite ends of cylinder 80 and which are equal in cross sectional area so that, during operation of the motor, the volume exhausted from one end of cylinder 80 is substantially the same as the volume of motive liquid supplied to the other end thereof.

Since all four rows of pump cylinders discharge through one of pipes 50 and 51 to the motor and only three rows of pump cylinders are supplied with liquid therefrom through the other of pipes 50 and 51, as previously explained, and since the volume discharged by the motor into one of pipes 50 and 51 is substantially equal to the volume supplied thereto through the other of pipes 50 and 51, it follows that more liquid is discharged by the motor than can be received by the three rows of pump cylinders connected thereto.

The liquid discharged by the motor in excess of the liquid that can be received by the three rows of pump cylinders is exhausted through an anti-jump valve 85 into a drain pipe 86 which discharges into reservoir 2.

In order that the liquid discharged by the motor in excess of pump requirements may be exhausted through anti-jump valve 85 in either direction of motor actuation, valve 85 is adapted to be connected to the discharge end of cylinder 80 in either direction of motor actuation. To this end, the casing of reversing valve 81 is connected by a pipe 87 to the inlet of anti-jump valve 85, by a pipe 88 to pipe 50 intermediate the ends thereof and by a pipe 89 to pipe 51 intermediate the ends thereof.

The function of valve 85 is to prevent a sudden variation in motor load from causing a material variation in motor speed as fully explained in Patent No. 2,071,781. Valve 81, which enables valve 85 to function during actuation of the motor in either direction, and valve 85 have not been shown in detail as they are fully illustrated and described in said patent. It is deemed sufficient to state that, when reversing valve 81 is in one position, liquid from gear pump 40-41 will flow through pipe 46, valve 81 and pipe 36 to cylinder 30 and move slide block 25 toward the right to the position shown in Fig. 2. Then the output of all of the cylinders will flow through pipe 50 to the left end of cylinder 80 and force piston 82 toward the right.

Piston 82 will discharge liquid from the right end of cylinder 80 into pipe 51. Enough of this discharge liquid to fill the pump cylinders in the three rear rows will flow thereto and the remainder of the discharge liquid will flow through

pipe 89, valve 81, pipe 87, anti-jump valve 85 and drain pipe 86 to reservoir 2.

A predetermined pressure is required to open anti-jump valve 85 which thereby causes a back pressure to be maintained upon motor piston 82 and the three rear rows of pump cylinders to be supercharged. It also causes a much higher momentary back pressure to be created in response to piston 82 tending to move at a speed greater than the predetermined speed as fully explained in Patent No. 2,071,781 referred to above.

When reversing valve 81 is shifted to its other position, the transmission will operate in the same manner but in the opposite direction. That is, liquid from gear pump 40-41 will flow through pipe 46, valve 81 and pipe 37 to cylinder 33 and shift slide block 25 toward the left and thereby cause the pump to deliver its entire output through pipe 51 to the right end of cylinder 80.

The liquid entering cylinder 80 will force piston 82 toward the left and cause it to discharge liquid into pipe 50. A part of the discharge liquid will flow through pipe 50 and communicating passages to the three rear rows of pump cylinders and the remainder of the discharge liquid will flow through pipes 50 and 88, reversing valve 81, pipe 87, anti-jump valve 85 and drain pipe 86 into reservoir 2. Anti-jump valve 85 will function as previously explained.

Figs. 6 to 12

The pump shown in these figures is non-reversible but many of its parts are exactly the same as and other of its parts are similar to the corresponding parts of the pump shown in Figs. 1 to 5. Consequently, like parts have been indicated by like reference numerals and no further description thereof will be given while similar parts have been indicated by corresponding reference numerals with the exponent "a" added.

Since the pump is non-reversible, it has been shown as having its slide block 25 arranged within a casing 1^a and provided with an adjusting screw 100 which extends outward through a cylinder 33^a formed in the side wall of the casing. Screw 100 has threaded thereon a hand wheel 101 which is journaled in and restrained from axial movement by a head 34^a which is fastened to the outer end of cylinder 33^a. Rotation of hand wheel 101 will cause slide block 25 to be moved transversely of casing 1^a and thereby vary pump displacement.

The pump has its cylinder barrel 11 journaled upon a pintle 6^a which is rigidly secured in the rear wall 3^a of the pump casing 1^a. Since the pump is non-reversible, all of the pump cylinders 19 may discharge into a single pintle port or into two communicating ports. As shown, the pump cylinders discharge into pintle ports 7^a and 8^a which communicate with each other and with two passages 55^a and 72^a formed in pintle 6^a longitudinally thereof.

Passages 55^a and 72^a communicate at the rear ends thereof with a passage 54^a which is formed in rear wall 3^a and extends transversely thereof into communication with a passage 52^a which extends rearward through the end of rear wall 3^a to permit the pump to deliver its output to an external circuit.

The three rear rows of pump cylinders 19 are supplied with liquid through a pintle port 8 and the front row of pump cylinders are supplied with liquid through a pintle port 10 as previously explained. Ports 8 and 10 communicate, re-

spectively, with two passages 57^a and 73^a which are formed in pintle 6^a longitudinally thereof.

Passage 57^a communicates at its rear end with passage 56^a which is formed in rear wall 3^a and extends transversely thereof into communication with a passage 53^a which extends rearward through the end of rear wall 3^a to permit the three rows of pump cylinders to be supplied with liquid from the external circuit to which passage 53^a is connected.

Passage 73^a communicates at its rear end with a passage 71^a which may be connected direct to reservoir 2 through check valve 66 and suction pipe 67 but which, in order to permit the pump to function as a non-differential pump, is shown connected to a bore 102 which is formed in rear wall 3^a and has a switch valve 103 arranged therein.

Bore 102 is connected to passage 56^a by a passage 69^a and to suction pipe 67 through a passage 65^a and check valve 66. Valve 103 is provided with two spaced apart heads or pistons 104 and 105 which are closely fitted in bore 102.

When valve 103 is in the position shown in Fig. 8, valve piston 104 blocks the end of passage 69^a so that liquid returned to the pump from an external circuit may flow to the three rear rows of cylinders only and the front row of cylinders must be supplied entirely from reservoir 2. When valve 103 is shifted toward the right, passage 69^a will be open to passage 71^a and all of the pump cylinders may be supplied from an external circuit or they may draw their supply either entirely or in part from reservoir 2.

For the purpose of illustration, the pump is shown in Fig. 10 as being employed to drive a differential hydraulic motor consisting of a stationary cylinder 110 and a piston 111 which is fitted in cylinder 110 and has a single piston rod 112 fixed thereto and extending through one end only of cylinder 110.

Operation of motor 110-111 is controlled by a reversing valve 113 arranged in a valve casing 114 and by a by-pass valve 115 arranged in a valve casing 116. For simplicity in illustration, valves 113 and 115 have been shown as being of the rotary type but in practice reciprocating or piston valves are preferably employed.

Reversing valve casing 114 is connected by two pipes 117 and 118 to opposite ends of cylinder 110, by a pipe 119 to by-pass valve casing 116, by a pipe 120 to passage 53^a in the rear wall 3^a of the pump casing, and by a pipe 121 to a drain pipe 122 which discharges into reservoir 2. Pipe 121 is connected to casing 114 between pipes 117 and 120 and has a low pressure relief valve 123 connected therein.

By-pass valve casing 116 is connected by a pipe 124 to passage 54^a in rear wall 3^a, by a pipe 125 to drain pipe 121 and by a pipe 126 to pipe 120 intermediate the ends thereof. At a point between pipe 126 and valve casing 114, pipe 120 is connected by a pipe 127 to the inlet of an anti-jump valve 128 which has its outlet connected by a pipe 129 to drain pipe 121. Anti-jump valve 128 is exactly the same as anti-jump valve 85 previously described and no further description thereof will be given.

When valve 103 is in the position shown in Fig. 8, valves 113 and 115 are in the positions shown in Fig. 10 and cylinder barrel 11 is rotating, liquid discharged from all four rows of pump cylinders will flow through pintle passages 55^a and 72^a, passage 54^a, passage 82^a, pipe 124 by-pass valve casing 116, pipe 119, reversing valve casing 114

and pipe 117 to the left end of cylinder 110 and force piston 111 toward the right on a working stroke.

Piston 111 will expel liquid from the right end of cylinder 110 through pipe 118 and reversing valve casing 114 into pipe 120. Enough of this liquid to fill the three rear rows of pump cylinders will flow thereto from pipe 120 through passages 53^a, 56^a and 57^a, and the remainder of the expelled liquid will be forced from pipe 120 through pipe 127 and anti-jump valve 128 and then flow through pipes 129, 121 and 122 to reservoir 2. At the same time, the front row of pump pistons will draw liquid into their cylinders from reservoir 2 through pipe 67, check valve 68, passage 65^a, bore 102 and passages 71^a and 73^a.

Since anti-jump valve 128 will not open until the pressure in pipe 120 reaches a predetermined value, it will cause a predetermined back pressure to be maintained on piston 111 during movement thereof at or near the predetermined speed, and it will cause a very high back pressure to be momentarily exerted thereon in response to piston 111 tending to jump forward as fully explained in my Patent No. 2,071,781 referred to above.

The hydraulic motor driven by the pump may be so proportioned that there will be little loss of power due to forcing liquid through the anti-jump valve. For example, if three-fourths of the pump cylinders are supplied with liquid from the motor and one-fourth of the pump cylinders are supplied with liquid from the reservoir, and if the ratio between the cross-sectional area of piston rod 112 and the cross-sectional area of piston 111 is .9:4, then during a given interval of time the pump will deliver 4 volumes of liquid to cylinder 110 and piston 111 will expel 3.1 volumes of which 3 volumes are consumed by the three rows of cylinders and only .1 volume is exhausted through anti-jump valve 128.

When reversing valve 113 is shifted to the position shown in Fig. 11, the liquid discharged by the pump will flow through pipe 124, by-pass valve casing 116, pipe 119, reversing valve casing 114 and pipe 118 to the right end of cylinder 110 and move piston 111 toward the left and cause it to expel liquid from the left end of cylinder 110 through pipe 117 into reversing valve casing 114. A part of the expelled liquid will flow through pipe 120 and communicating with passages to the three rear rows of pump cylinders and the remainder of the expelled liquid will flow into drain pipe 122 through resistance valve 123 which offers enough resistance to the flow of liquid therethrough to insure filling of the pump cylinders.

When by-pass valve 115 is shifted to the position shown in Fig. 12, pipe 124 is open to return pipe 128 through pipe 126 and to drain pipe 122 through pipe 125 so that the liquid discharged by the pump may be in part returned direct to the pump cylinders to fill the same and in part exhausted into reservoir 2, thereby preventing motor 110-111 from operating.

The invention herein set forth is susceptible of various modifications and adaptations without departing from the scope thereof as hereafter claimed.

The invention is hereby claimed as follows:

1. In a pump having an outlet and a first and a second inlet, the combination of a plurality of cylinders, a piston fitted in each cylinder, means for reciprocating said pistons to cause the same to draw liquid into said cylinders and discharge it therefrom, valve means for directing the liquid

discharged from all of said cylinders to said outlet and for directing liquid from said first inlet to a part only of said cylinders and for directing liquid from said second inlet to the remainder of said cylinders, and means for reversing said pump without altering the number of cylinders delivering liquid to said outlet or the number of cylinders receiving liquid from said first inlet.

2. A differential pump, comprising a valve member having intake and discharge ports arranged therein, a rotatable cylinder barrel engaging said valve member and provided with a plurality of cylinder ports each of which communicates with an intake port and a discharge port alternately as said cylinder barrel rotates, a plurality of cylinders arranged in said cylinder barrel and each communicating with a cylinder port, a piston fitted in each cylinder, means for reciprocating said pistons during rotation of said cylinder barrel, said valve member being so constructed and connected in circuit that it combines the output of all of said cylinders and directs liquid from one source to a part only of said cylinders and liquid from another source to the remainder of said cylinders, and means for reversing said pump without altering the number of cylinders which receive liquid from each of said sources.

3. A differential pump, comprising a valve shaft or pintle having intake and discharge ports and passages arranged therein, a rotatable cylinder barrel journaled upon said pintle and provided with a plurality of ports each of which communicates with an intake port and a discharge port alternately as said cylinder barrel rotates, a plurality of cylinders arranged in said cylinder barrel and each communicating with a cylinder port, a piston fitted in each cylinder, means for reciprocating said pistons during rotation of said cylinder barrel, said ports and passages being so arranged that the output of all of said cylinders may be combined into a single stream and that liquid may be supplied to a part only of said cylinders from one source and to the remainder of said cylinders from a different source, and means for reversing said pump without altering the number of cylinders which receive liquid from each of said sources.

4. A differential pump, comprising a valve member having an intake port formed therein upon one side of the center thereof for connection to one side of an external hydraulic circuit, a second intake port formed therein upon the same side of the center thereof for connection to a separate source of fluid supply and at least one discharge port formed therein upon the opposite side of the center thereof for connection to the other side of said circuit, a rotatable cylinder barrel engaging said valve member and provided with a plurality of ports each of which communicates with an intake port and a discharge port alternately as said cylinder barrel rotates, a plurality of cylinders arranged in said cylinder barrel and each communicating with a cylinder port, a piston fitted in each cylinder, means for reciprocating said pistons during rotation of said cylinder barrel, and means for reversing said pump without altering the number of cylinders that are supplied with liquid from said separate source.

5. A differential pump for supplying liquid to a hydraulic circuit, comprising two separate sets of pistons and cylinders, means for actuating said pistons, means for connecting the cylinders of one set to the pressure and return sides of

said circuit alternately whereby the cylinders of that set receive liquid from the return side of said circuit and discharge into the pressure side thereof, and means for connecting the cylinders of the other set to the pressure side of said circuit and to a separate source of liquid supply alternately whereby the cylinders of that set receive liquid from said source and discharge into the pressure side of said circuit.

6. A differential pump, comprising a valve member provided in one half thereof with a discharge port and in the opposite half thereof with two intake ports having no communication with each other, a rotatable cylinder barrel engaging said valve member and having a plurality of cylinder ports arranged therein in two circular rows, the ports in one row communicating with one of said intake ports and said discharge port alternately and the ports in the other row communicating with the other of said intake ports and said discharge port alternately during rotation of said cylinder barrel, a plurality of cylinders arranged in said cylinder barrel and each communicating with a cylinder port, a piston fitted in each cylinder, means for reciprocating said pistons during rotation of said cylinder barrel, and means for connecting said intake ports to separate sources of liquid supply.

7. A differential pump, comprising a valve member having two intake ports and two discharge ports formed therein upon opposite sides of the center thereof, a rotatable cylinder barrel engaging said valve member and having a plurality of cylinder ports arranged therein in two circular rows, the ports in each row communicating with one intake port and one discharge port alternately as said cylinder barrel rotates, a plurality of cylinders arranged in said cylinder barrel and each communicating with a cylinder port, a piston fitted in each cylinder, means for reciprocating said pistons during rotation of said cylinder barrel, means for connecting one of each of said intake and discharge ports to an external circuit, means for connecting the other discharge port to said circuit, and means for connecting the other intake port to a separate source of liquid supply.

8. A reversible differential pump, comprising a valve member having two intake ports and two discharge ports formed therein upon opposite sides of the center thereof, a rotatable cylinder barrel engaging said valve member and having a plurality of cylinder ports arranged therein in two circular rows, the ports in each row communicating with one intake port and one discharge port alternately as said cylinder barrel rotates, a plurality of cylinders arranged in said cylinder barrel and each communicating with a cylinder port, a piston fitted in each cylinder, means for reciprocating said pistons during rotation of said cylinder barrel, means for reversing said pump to thereby reverse the direction of flow through said pintle ports, means for connecting one of each of said intake and discharge ports to an external circuit, and means for connecting each of the other two pintle ports to said circuit and to a separate source of liquid

supply selectively responsive to reversal of liquid flow.

9. A reversible differential pump, comprising a valve shaft or pintle having two opposed main ports and two opposed auxiliary ports formed therein, a rotatable cylinder barrel journaled upon said pintle and having a plurality of cylinder ports arranged therein in two circular rows, the ports in each row communicating with two opposed pintle ports alternately as said cylinder barrel rotates, a plurality of cylinders arranged in said cylinder barrel and each communicating with a cylinder port, a piston fitted in each cylinder, means for reciprocating said pistons during rotation of said cylinder barrel, means for reversing said pump to thereby reverse the direction of flow through said pintle ports, fluid channels for connecting said main ports to an external circuit, means for connecting one of said auxiliary ports to said circuit, means for connecting the other auxiliary port to a source of liquid supply, and means for reversing said connecting means.

10. A reversible differential pump, comprising a valve shaft or pintle having two opposed main ports and two opposed auxiliary ports formed therein, a rotatable cylinder barrel journaled upon said pintle and having a plurality of cylinder ports arranged therein in two circular rows, the ports in each row communicating with two opposed pintle ports alternately as said cylinder barrel rotates, a plurality of cylinders arranged in said cylinder barrel and each communicating with a cylinder port, a piston fitted in each cylinder, means for reciprocating said pistons during rotation of said cylinder barrel, means for reversing said pump to thereby reverse the direction of flow through said pintle ports, fluid channels for connecting said main ports to an external circuit, means including a valve for connecting one of said auxiliary ports to said circuit and the other auxiliary port to a source of liquid supply, and means responsive to a reversal of flow through said pintle ports for shifting said valve.

11. A pump, comprising a valve shaft or pintle provided in one side thereof with a discharge port and in the opposite side thereof with two intake ports having no communication with each other, a rotatable cylinder barrel journaled upon said pintle and having a plurality of cylinder ports arranged therein in two circular rows, the ports in one row communicating with one of said intake ports and said discharge port alternately and the ports in the other row communicating with the other of said intake ports and said discharge port alternately during rotation of said cylinder barrel, a plurality of cylinders arranged in said cylinder barrel and each communicating with a cylinder port, a piston fitted in each cylinder, means for reciprocating said pistons during rotation of said cylinder barrel, and means including a valve for selectively connecting said intake ports to separate sources of liquid supply or to a single source.

JAMES K. DOUGLAS.
